(57) **CLAIM**

The ornamental design for a seat cover, as shown and described.

DESCRIPTION

FIG. 1 is a top, front perspective view of a seat cover on a seat;

FIG. 2 is front view of the seat cover of FIG. 1;

FIG. 3 is a rear view thereof;

FIG. 4 is a left side view thereof;

FIG. 5 is a right side view thereof;

FIG. 6 is a top view thereof; and,

FIG. 7 is a bottom view thereof.

In FIG. 1, the broken lines representing a seat underneath the seat cover depict environmental subject matter that forms no part of the claimed design. All other broken lines and areas enclosed within them depict portions of the seat cover that form no part of the claimed design.

1 Claim, 6 Drawing Sheets
